UNITED STATES PATENT OFFICE.

HENRY HALES, OF HAVRE, MONTANA.

WEEDER.

1,254,687.

Specification of Letters Patent.

Patented Jan. 29, 1918.

Application filed June 28, 1916. Serial No. 106,345.

To all whom it may concern:

Be it known that I, HENRY HALES, a citizen of the United States, and a resident of Havre, in the county of Hill and State of Montana, have invented a new and Improved Weeder, of which the following is a full, clear, and exact description.

The invention relates to weeder and has for its object to so mount the knives that they can be set to or cut in a horizontal plane or at angles thereto.

A further object of the invention is to mount the knives so that they will move to one side when they come in contact with an immovable object and when the object is passed will be returned to normal position.

A practical embodiment of the invention is shown in the accompanying drawing forming a part of this specification and in which similar characters of reference indicate corresponding parts in all of the views.

Figure 1 is a perspective view of the improvement,

Fig. 2 is a detail view of the standard and blade partly in section,

Fig. 3 is a perspective view of a modification and

Fig. 4 is a longitudinal section of the same with the knife standard removed.

Referring to Figs. 1 and 2, 5 is a beam of the frame of a weeder, in which the knives are mounted. A sleeve 6 mounted in the beam 5 is provided at its upper end with a disk 7 and in said sleeve is mounted the tubular shaft 8.

In the lower end of the tubular shaft 8, the square upper end of the standard 9 is adjustably secured by the set screw 10 and to the lower end of the standard the knife 11 is secured. The knife 11 is provided with a shank 12 which terminates in an arc-shaped member 13 provided with a curved slot 14. The member 13 of the shank 12 of the knife fits into the curved face of a block 15, whose other face is roughened to fit against the roughened surfaces of the lower end of the standard 9, and a bolt 16 passes through the slot of the shank of the knife, the block and standard. By thus securing the knife to the standard the knife

can be adjusted to cut in a horizontal plane or at angles thereto.

Upon the upper end of the sleeve 6, below the disk 7 thereof, is the disk 17 and a bolt 18 passes through the hub of the disk and the sleeve 6 into the tubular shaft 8. A coil spring 19 on the sleeve has one end secured to the beam 5 and the other end to the bolt 18. The disk 7 is provided with a plurality of openings 7^a and the disk 17 with an opening 17^a, and through said openings a pin 20 passes. By this construction the knife will turn to one side whenever it meets an obstruction and will return to normal position after the obstruction is passed. To increase the tension of the spring the bolt 18 and pin 20 are removed and the disk 17 rotated to the desired extent, after which the bolt and pin are again replaced.

In Figs. 3 and 4 the construction is the same as that shown in Figs. 1 and 2 with the exception that instead of a tubular shaft, in which the knife standard is mounted, a solid shaft 21 having a socket 21^a at its lower end to receive the knife standard is employed.

By my means of mounting the knife, it can be readily and quickly set to cut at different angles and will readily yield when meeting an obstruction, thereby preventing breakage. My means is also very simple and cheap.

What I claim is:

1. In an agricultural implement, a frame, a shaft mounted to turn in the frame, a spring connected with the upper end of the said shaft, a standard vertically adjustable in the shaft, a substantially horizontal blade provided with a vertical shank at one end, and means for adjustably securing the shank to the lower end of the standard, whereby the blade may be set to cut in a horizontal plane or at angles thereto.

2. In an agricultural implement, a frame, a tubular shaft mounted to turn in the frame, an adjustable spring device connected with the upper end of the shaft, a standard vertically adjustable in the shaft, a substantially horizontal blade provided with a vertical shank at one end and means for adjustably securing the shank of the

knife to the standard to set the blade at different angles.

3. In an agricultural implement, a frame, a tubular shaft mounted to turn in the shaft, a spring connected with the said shaft, a standard vertically adjustable in the shaft, a substantially horizontal blade provided with a vertical shank having an enlarged

and arc-shaped upper end provided with a curved slot, a block between the standard and 10 the shank of blade and having an arc-shaped face with which the enlarged arc-shaped end of the shank engages, and a bolt passing through the standard, block and slot of the shank of the blade.

HENRY HALES.
